UNITED STATES PATENT OFFICE

2,451,011

APPARATUS FOR FILLING CONTAINERS

Fred P. Yoars, New Orleans, La.

Application April 21, 1945, Serial No. 589,587

5 Claims. (Cl. 226—94)

1

This invention relates to apparatus for filling containers.

The invention is more particularly concerned with apparatus for successively filling containers with a semi-solid material such as, ice-cream, sherbets, and the like, through a continuous flow of the material from a dispensing apparatus.

In apparatus heretofore employed for filling containers with semi-solid materials both mechanical and manual means have been used. With both of such means, however, the material has been intermittently delivered in measured quantities to the containers, thus necessitating a dispensing operation in the filling of each container or a series thereof.

A primary object of the present invention is the provision of apparatus for rapidly filling containers in succession from a continuous flow of semi-solid material with substantially uniform quantities of material in the containers and without dripping or waste of the material.

A further object of the invention is the provision of manually controlled apparatus for yieldably supporting a container-bearing rack beneath a material-dispensing means, whereby the rack is capable of being easily and rapidly moved both vertically and horizontally for successively placing the containers in filling position and wherein the rack is movable vertically to an extent to break the flow of the viscous semi-solid material such that the successive containers are capable of being moved into filling position without waste or drip from a continuous flow of the semi-solid material.

A still further object of the invention is the provision of a novel apparatus of the above noted character which is relatively simple in construction, durable, efficient in operation, and which in use provides for the filling of containers expeditiously, and with minimum effort on the part of an operator.

Other objects and advantages will become apparent from the following detailed description taken in connection with the accompanying drawings, wherein:

Figure 1 is a perspective view of the apparatus disclosing the novel apparatus for successively filling containers with a semi-solid material having a continuous flow from a dispensing means.

Fig. 2 is a side elevational view of the apparatus showing the operation thereof upon manual lowering of the container-supporting rack preparatory to advancing another container or series of containers to the dispensing means.

Fig. 3 is an end elevation as seen from the right

2

of Fig. 2 and showing the apparatus in a position corresponding to that indicated in broken lines in Fig. 2, this figure also showing the breaking of the flow of material to permit advancing another container into filling position without drip or waste of the material.

Referring now in detail to the drawings, T designates a plurality of material discharge tubes which are jointly provided with a nipple n for detachable connection with a suitable dispensing apparatus operative to force the semi-solid material in a continuous flow through and out of the tubes. While three such tubes are shown, more or less may be used, dependent upon the number of containers or cups in the successive series thereof as arranged in a rack R.

The apparatus for supporting the rack R and permitting both vertical and horizontal movement thereof comprises a suitable table top 10 supported by vertical legs 11 which adjacent their lower ends are interconnected by the brace members 12 and 13.

An inverted U-shaped member or bail 14 has the base thereof extending above and parallel with the table top and the opposed legs thereof, extending through elongated slots 15 in the table top. Pivotedly connected at 16 to the legs of member 14 adjacent the base thereof are corresponding ends of bars 17 whose opposite ends are pivotally connected at 18 to vertically disposed ears 19 on the opposed ends of a slat 20 suitably secured as at 20' to the table top adjacent one end thereof.

The lower ends of the legs of member 14 beneath the table top are pivotally connected at 21 to corresponding ends of arms 22 whose opposite ends are connected with trunnions 23 suitably supported in cushion devices 24. These devices 24 are provided with brackets 25 which are secured as at 25' to the lower face of the table top.

The cushion devices may be of any well known form and which function to yieldably maintain the member 14 in raised position as in Fig. 1 or as in full lines in Fig. 2 while permitting downward movement of such member with substantially little effort by an operator manually manipulating the rack R, as in Fig. 1.

The base of the bail 14 is preferably provided with a strip or bar 27 for support of the lower side wires s of the rack, and in order to restrain the rack against lateral movement suitable guide members 28 are secured to bar 27 and projecting thereabove, the guide members resting closely within the side wires s. The bar 27 is preferably

rounded to provide for ease of movement of the rack.

The cushion devices resist downward movement of arms 22 only to an extent such that the rack R with its load of cups or containers C is supported when held by the hands of an operator as indicated in Fig. 1, but such devices readily yield upon urging the rack downwardly by the hands with substantially little effort upon the part of an operator.

In operation of the apparatus an operator grasps a rack R at opposite ends thereof by her hands, as indicated by dotted lines in Fig. 1. The rack is then positioned on the strip 27 and the endmost series of cups C are brought under the tubes T, which tubes in the raised position of the rack project into the cups. As the cups fill the rack is gradually lowered and when the cups are filled the rack is quickly depressed, as in Figs. 2 and 3, wherein the tops of the cups are spaced from the lower ends of the tubes at such a distance that the flow of material is broken, as indicated at b in Fig. 3, which, together with the viscous nature of the material, permits longitudinal movement and then elevation of the rack with the second series of cups beneath the tubes without spilling any of the material. When the second series of cups are filled, a like movement is imparted to the rack and the cups supported thereby.

Little skill is required to manually manipulate the apparatus and an operator after having had simple instructions will be able to manipulate the apparatus in the manner above described.

It will be appreciated from the foregoing disclosure that the improved apparatus provides for the expeditious filling of containers by substantially unskilled operators and, due to the continuous flow of the material, it is only necessary to support the rack on the strip 27 and keep moving same with minimum effort, whereby a large number of containers is capable of being filled in a minimum period of time and with assurance that the material will not drip onto the table top or otherwise be wasted.

Furthermore, by this means of filling, wherein measured quantities of the material are not dispensed as in previous methods, the successive cups will be filled with substantially uniform quantities of the material.

While I have disclosed the invention in accordance with a single specific embodiment thereof, such is to be considered as illustrative only and not restrictive, the scope of the invention being defined in the subjoined claims.

What I claim and desire to secure by U. S. Letters Patent is:

1. Apparatus for supporting a container-holding rack beneath a semi-solid material filling tube for movement of the rack toward and from the tube as well as horizontally for successive filling of the containers, comprising a rigid horizontal base support, a horizontally disposed rack engaging bar disposed above the base support and having laterally disposed legs integral therewith

extending downwardly through slots in the base support, pivotal connections between the base support and the upper ends of the legs, and yieldable means disposed below the base support having pivotal connection with the lower ends of the legs for urging the rack-supporting bar upwardly while offering little resistance to manual lowering of the bar, said bar having a rounded rack-engaging surface, and laterally disposed rack-engageable guides connected to the bar and projecting thereabove.

2. Apparatus for the purpose set forth, including a horizontally disposed table top, an inverted U-shaped member having a horizontal base portion disposed above the table top and laterally disposed legs projecting through slots in the table top, a pair of laterally disposed bars having corresponding ends thereof pivotally connected with the legs adjacent the upper ends thereof and having their opposite ends pivotally connected with the table top adjacent one end thereof, a pair of laterally spaced cushion devices supported beneath the table top, and an arm operatively connected with each cushion device and having its free end pivotally connected with the lower end of a respective one of said legs.

3. Apparatus according to claim 2, together with a rack supporting strip secured to said base portion.

4. Apparatus according to claim 2, together with rack guide members secured to said base portion adjacent said legs.

5. Apparatus for supporting a container-holding rack beneath a semi-solid material-filling tube for movement of the rack toward and from the tube as well as horizontally for successive filling of the containers, comprising a rigid horizontal base support, a horizontally disposed rack-engaging bar disposed above the base support and having laterally disposed legs extending through slots in the base support, pivotal connections between the base support and the upper ends of the legs, and yieldable means disposed below the base support having pivotal connections with the lower ends of the legs for urging the rack-supporting bar upwardly while offering little resistance to manual lowering of the bar, said yieldable means being secured beneath the base support, and said pivotal connections of the yieldable means with the legs comprising arms operatively connected with the yieldable means.
